MATVEY ALCUNOVITCH CAPELIUSCHNICOFF, OF BAKU, RUSSIA.

APPARATUS FOR BORING WELLS AND THE LIKE.

Application filed August 18, 1924, Serial No. 732,779, and in Great Britain September 11, 1923.

This invention relates to the drilling of bore holes, as in well sinking, by means of a rotary drilling apparatus of the kind in which water or the slush pumped from the well is supplied under pressure through a tube or a series of connected tubes, which do not rotate, to a hollow drill head or chamber in which is mounted a hydraulic rotor or turbine which is driven by the said 10 water supply and which drives through gearing a spindle or tubular stem carrying the cutting tool or bit, the water discharged from the turbine being directed towards the bottom of the bore hole to entrain the débris 15 produced by the boring and facilitate its discharge from the well.

The present invention consists in an improved construction of apparatus of this class in which the drilling bit is driven by 20 a hydraulic turbine through a train of epicyclic gears whereby the necessary reduction ratio between rotor spindle and drill spindle can be obtained within a very small diametral space. Further, by using an axial flow 25 turbine with fixed guide ring a low water consumption and low turbine speed are obtained, and this in conjunction with the epicyclic transmission gear makes it possible to run the drill spindle at as low a speed as 30 desirable to obtain maximum torque on the drill.

The upper bearing of the turbine rotor spindle is contained in the turbine guide ring which is screwed into the internally 35 threaded casing or shell of the drill head or chamber, thereby ensuring permanence in the positional relation of the bearing and the rotor spindle and obviating any necessity for adjustment each time the parts are 40 assembled.

Also the entire body of water discharged from the turbine after being by-passed around the transmission gear is passed into the interior of the hollow driving spindle 45 and thence to the hollow drill which is provided with suitable apertures for discharging the water or slush against the bottom of the bore hole.

These and other features of the invention 50 are hereinafter described with reference to the accompanying drawings, in which Fig. 1 is a diagrammatic representation of the equipment required for carrying out the method of operation involved in the present 55 invention, and Figs. 2 and 3 are respectively

a longitudinal and a transverse section of a drill head embodying the invention.

A pump A, operating through a hydraulic accumulator B, forces the slush into the bore hole through non-rotating pipes C for the 60 purpose first of driving the rotary boring apparatus indicated by D which operates the drill E, and secondly for loosening and bringing up to the surface the spoil of the 65 drill.

The boring apparatus includes a hollow drill head D which is connected with the non-rotating drill-piping C. In the upper end of the casing D is a hydraulic rotor or 70 turbine F which is driven by the water or slush forced into the bore hole by pump A. The rotor spindle F', which is journaled at its upper end in bearings in the stationary 75 guide or nozzle ring F² of the rotor, drives the drill socket member G through an epicyclic train of gears H, I, I', I², I³, J, the planet wheels I', I², I³ being carried on stub shafts secured in the drill socket member G which is caused to rotate about the common 80 axis by the engagement of the planet gears with an internally toothed portion of an inner casing or sleeve L secured to the hollow drill head D. Thrust bearings K are provided between shoulders G', G² on the 85 drill socket member and an annular flange L' on the sleeve L secured to the drill-piping C which sleeve, together with a cap or cover M encircling the rotary spindle F', forms a closed casing for the driving gears. The gears are designed to give an appropriate 90 reduction of speed according to the character of the work to be done and the construction is such as to permit a ready interchange of gears for changing the speed of working. The water or slush, after passing through the vanes of the rotor F, traverses ducts L² in the sleeve L leading to the interior of the drill socket G and thence through suitable apertures in the hollow bit 95 to the point of working of the drill. 100

Having thus described the nature of the said invention and the best means I know of carrying the same into practical effect, I claim:—

1. In well-drilling apparatus of the character described, the combination of a hollow drill head, an axial flow hydraulic turbine having a fixed ring screwed into the hollow drill head, a bearing within the said guide ring, a rotor spindle journaled at its up- 105 110

- per end in said bearing, a drill socket member journalled in the lower end of the hollow drill head, an inner sleeve secured to the drill head and having an internally 5 toothed portion, planetary gears journalled on stub shafts carried by the drill socket member and a gear wheel on the hydraulic turbine rotor spindle meshing with said planetary gears.
- 10 2. In well-drilling apparatus of the character described, the combination of a hollow drill head, an inner sleeve secured thereto, an axial flow hydraulic turbine having a fixed guide ring secured in the upper part of 15 the hollow drill head, a hollow drill socket member journalled in the lower part of the said drill head and closing the lower end of said inner sleeve, a cap encircling the turbine rotor spindle and closing the upper 20 end of the fixed sleeve, an epicyclic gear train enclosed within the sleeve and connecting the turbine rotor spindle with the hollow drill socket member, and passages in the wall of the latter member establishing 25 communication between its interior and the space between the hollow drill head and the inner sleeve.
3. In well-drilling apparatus of the character described, the combination of a hydraulic turbine, a drill spindle, reduction gear interposed between the turbine shaft and the drill spindle, an inner casing or 30 sleeve enclosing said reduction gear, an outer shell or drill head, fluid passages between said inner casing and drill head, a 35 hollow drill socket forming part of the drill spindle, said hollow socket having apertures connecting the interior thereof with the said fluid passages, and a hollow bit secured to said hollow socket and provided with outlet 40 apertures.
4. In well-drilling apparatus of the character described, the combination of a hydraulic turbine, a drill spindle, epicyclic reduction gear interposed between the turbine 45 shaft and the drill spindle, a fixed inner casing or sleeve enclosing said reduction gear, said fixed inner casing having on its inner face an internal toothed gear meshing with the planet wheels of said epicyclic reduction gear, stub shafts on the head of said drill spindle carrying the said planet wheels, a sun gear wheel fast on the turbine shaft meshing with said planet wheels, said drill spindle having shoulders and said fixed 55 inner casing having an internal flange, and thrust bearings between said shoulders and said internal flange whereby shocks on the drill spindle in either direction are transmitted directly to the said fixed casing. 60

In testimony whereof I have signed my name to this specification.

MATVEY ALCUNOVITCH CAPELIUSCHNICOFF.
